United States Patent Office.

WILLIAM W. BEACH, OF NEW YORK, N. Y.

Letters Patent No. 66,448, dated July 9, 1867.

IMPROVED INKSTAND AND MUCILAGE-HOLDER COMBINED.

The Schedule referred to in these Letters Patent and making part of the same.

TO ALL WHOM IT MAY CONCERN:

Be it known that I, Dr. WILLIAM W. BEACH, of the city and State of New York, have invented, made, and applied to use a certain new and improved Inkstand and Mucilage-Holder Combined; and I do hereby declare the following to be a full, clear, and exact description of the said invention, reference being had to the annexed drawing, making part of this specification, wherein I have represented a vertical section of said inkstand and mucilage-holder combined.

Ink and mucilage are required very generally by accountants, merchants, and others, and heretofore the mucilage-holder has been entirely separate from the inkstand. By combining the two no more space is required on the desk that is usually occupied by the vessels separately, and the base of the inkstand can be broad and firm, and the mucilage-receptacle within or connected with said inkstand is always in a convenient position for use. The brush in my mucilage-receptacle only is immersed, and is in a position to be easily grasped and used.

In the drawing I have shown an inkstand composed of the saucer *a*, ink-vessel *b*, cup *c*, on the side, and displacer *d*, to cause the ink to rise in the cup as said displacer is forced down, but this inkstand may be of any desired size or character to which the mucilage-receptacle can be applied with facility. I make the displacer *d* hollow, and form a screw upon its outside, so that it can be screwed up or down through the cap *e*, according to the height of ink or quantity in the fountain. The cap *e* and vessel *b* may be made together. This hollow displacer I make use of for receiving the mucilage-brush and fountain, the same forming a cup. *f* is the mucilage-fountain, shown as inverted into the cup *d*, and provided with a brush, *g*, at the mouth or neck, with a hole through the brush to allow the mucilage to pass to the brush as required. When inverted into the cup *d*, the brush *g* is immersed in the mucilage in said cup, and is kept moist and in condition for use, and the mucilage cannot run out of the fountain *f*, because its mouth is immersed. The brushes can be screwed into the neck of the fountain, so as to be removable to introduce a brush of a different size or shape, or to supply a new one when required. The character of inkstand may be varied as required, so long as provision is made in the same for the mucilage.

What I claim, and desire to secure by Letters Patent, is—

A mucilage-receptacle and inkstand combined, substantially as and for the purposes set forth.

I also claim the displacer *d*, formed with a screw on the outside for adjusting said displacer in the ink, and a cup on its inside for the reception of mucilage, substantially as set forth.

In witness whereof I have hereunto set my signature this eleventh day of May, A. D. 1867.

WM. W. BEACH.
